2,257,356

METHOD OF MAKING ORNAMENTAL CHAINS

Karl Wacker, Pforzheim, Germany, assignor to
Armbrust Chain Company, a corporation of
Rhode Island

Original application February 13, 1939, Serial No.
256,073, now Patent No. 2,229,149, dated Janu-
ary 21, 1941. Divided and this application
January 3, 1940, Serial No. 312,282

2 Claims. (Cl. 59—35)

This application is a division of application Se-
rial No. 256,073, filed February 13, 1939, for Or-
namental chain.

My present invention relates to the jewelry art,
and has particular reference to a novel machine
for making ornamental chains.

It is the principal object of my invention to
provide an automatic mechanism which is par-
ticularly suitable for the production of hollow
chain links.

Another object of my invention is to provide an
automatic mechanism which will permit manu-
facture of hollow chains having a designed cross
section.

An additional object of my invention is to pro-
vide a novel mechanism of the type described for
the manufacture of ornamental filled links.

With the above objects and other advanta-
geous features in view, my invention consists of
a novel arrangement of parts more fully dis-
closed in the detailed description following, in
conjunction with the accompanying drawings,
and more specifically defined in the claims ap-
pended thereto.

In the drawings:

Fig. 1 is a plan view of a novel machine ar-
rangement for use with a standard chain making
machine;

Fig. 2 is a side view thereof;

Fig. 3 is a horizontal section through Fig. 2;

Fig. 4 is a perspective view of the upper rear
portion of the forming die;

Fig. 5 is a perspective view of the lower rear
portion of the forming die;

Fig. 5a is a perspective view of a modified low-
er rear portion of the forming die;

Fig. 6 is a vertical section of the front portion
of the former die;

Fig. 7 is a sectional detail showing the housing
for the forming die;

Fig. 8 is a section on the line 8—8 of Fig. 2;

Fig. 9 is a perspective view of a strip of orna-
mental metal;

Fig. 10 is a perspective view showing the form-
ing of the sheet strip into tubular form after
passage through the former die;

Fig. 11 is a perspective view of a filler rod;

Fig. 12 is a perspective view of the shaping of
the strip, using the filler rod of Fig. 11; and

Fig. 13 is a perspective view of the novel helical
coil formed.

It has been found desirable to provide an at-
tachment for a chain making machine, which
will automatically manufacture ornamental
chain links of either hollow or filled construction.

To this end, I have provided a novel former die
arrangement which receives a flat strip of orna-
mental metal, as from a roll, and shapes the
ornamental metal into tubular form, an inner
5 filler being used if desired. After the orna-
mental metal has been shaped into tubular form,
it is received by a screw feeder which automatic-
ally winds the shaped tubular metal into helical
form and feeds the helical tubular metal to the
10 standard cutting and joining mechanism of the
chain machine.

Referring to the drawings, the novel attach-
ment 20 includes a power actuated crank 21
which is pivotally connected as at 22 to an oscil-
15 lating rack 23, mounted for sliding movement in
the frame of the chain machine. The rack 23
meshes with a geared hub 24 which is rotatably
supported in a fixed bearing 25, the hub 24 hav-
ing a central bore 26 within which a shaft 27 is
20 slidably mounted. As shown in Fig. 3, the hub
24 has an annular collar 28 keyed thereto in any
desired manner, this annular collar having a plu-
rality of rods 29 which are parallel to and con-
25 centric with shaft 27, mounted therein and
locked thereto by means of set screws 30. A hub
31 is keyed, or otherwise secured to the shaft 27,
as by means of lock screws 32, and has a plurality
of transverse parallel bores 33 which slidably re-
ceive the rods 29.

30 A worm gear 34 is keyed to one end of the
shaft 27, as by means of a lock screw 35, and is
provided with a helical groove 36, the worm gear
being rotatably supported in a fixed bearing 37
35 which has a fixed pin 38 secured thereto and ex-
tending into the groove 36, whereby oscillation of
the shaft 27 and the worm gear 34 produce a re-
ciprocation of the shaft. The end of the shaft is
formed with a spiral worm 39, having a helical
groove 40 for the purpose hereinafter described.

40 Referring to Figs. 4 to 8, the chain machine is
provided with a stationary housing arrangement
41 for receiving the former die, a circular recess
42 therein housing the die, and an aperture 43
45 being provided in the forward portion of the
housing for the exit of the shaped tubular strip.
A front former die 44 is seated in the forward
portion of the cavity 42, and has a conical bore
46; two rear former dies cooperate with the
front die, these dies respectively consisting of an
upper half die 46 having a convex portion 47 and
50 a lower rear portion 48 having a tapered flat re-
cessed seat 49 and a central arcuate portion 50,
the upper and lower die portions fitting as shown
in Fig. 8. If desired, the lower die may be shaped
as indicated at 51 in Fig. 5a, with a flat recessed

slanted portion 52, the central arcuate portion being omitted.

A strip of ornamental metal 53 such as disclosed in Fig. 9, which is preferably in a roll, is fed into the rear portion of the former die on the recessed surface 49. A stationary rod 54, having a conical end, is positioned to seat in the recess 50, so that forward movement of the strip 53 shapes the strip to provide a tubular rod 54, as disclosed in Fig. 10. If it be desirable to use a filler, a rod of filler material 55 may be inserted in the arcuate die cavity 50, and the tubular rod 56, as disclosed in Fig. 12, will then have a filler in the center thereof, whereby inexpensive material may be used inside the outer layer of more expensive ornamental material.

Referring now to Fig. 3, the tubular rod emerging from the former die is wound into the groove 40 of the shaft extension 39, the size of the groove 40 preferably gradually increasing slightly toward the free end, so as to provide greater frictional engagement at the initial winding of the tubular rod with the sides and bottom of the groove 40. With the tubular rod initially wound into the groove 40, operating the machine actuates the crank and thus rocks the rack to impart an oscillating motion to the shaft 27, whereby engagement of the fixed pin 38 with the helical groove 36 feeds the shaft 27 and its spiral end 39 forwardly and backwardly during the revolution of the crank, the forward feeding gripping the tubular rod 54 and winding it forwardly into a helical coil 57, and the backward movement winding the shaft end back through the helical coil 57, the helical coil giving sufficiently to permit free backward movement of the shaft end and thus exposing an end portion 58 of a size to form at least one link to the cutting mechanism of the chain machine.

The groove 40 may be cut to accommodate any desired shape or cross section of the tubular rod, whereby a former die of appropriate shape and a matching thread 40 cooperate to form links of desired contour, which are either hollow, or are solid with a filler of metal or other suitable material.

The novel machine attachment thus forms

strips of ornamental material into tubular form of any desired cross section, winds the tubular formed material into helical form, and feeds the helical tubular material forwardly so as to expose sufficient length thereof to permit cutting for forming a chain portion, the forward movement covering a winding and a resulting gripping, and the backward movement unwinding the coil to release the gripping. Any desired ornamental material may be used, metal being the preferred material, and any desired material may be used for a filler, whereby a light tubular chain or a heavier filled chain is readily obtained.

While I have described a specific constructional embodiment of my improved chain machine attachment, it is obvious that changes in the arrangement and operation of the parts in order to obtain different sizes of links for the completed chain, different thicknesses of links, and different cross sections or contours for the links, may be made to suit the requirements for different ornamental chain designs, without departing from the spirit and the scope of the invention as defined in the appended claims.

I claim:

1. In the manufacture of ornamental chains, the steps of feeding a longitudinal strip of material through a forming die to bring the edges together and provide a tubular rod section and then through a rotating and reciprocating helical groove die to wind the tubular rod section into a helix, and successively cutting off chain portions from the end of said helix emerging from the groove die.

2. In the manufacture of ornamental chains, the steps of feeding a longitudinal strip of material through a forming die and simultaneously feeding a filler rod to bring the edges of the strip together around said filler rod for providing a tubular rod section having a filler rod positioned therein and then through to a rotating and reciprocating helical groove die to form a helix, and successively cutting off chain portions from the end of said helix emerging from the groove die.

KARL WACKER.
